UNITED STATES PATENT OFFICE.

CHARLES M. FITCH, OF KANKAKEE, ILLINOIS, ASSIGNOR TO SEARS, ROEBUCK AND CO.,
OF CHICAGO, ILLINOIS, A CORPORATION OF NEW YORK.

BURNER-REGULATING MECHANISM.

Application filed October 21, 1925. Serial No. 63,815.

This invention relates to wickless oil burners and in particular to a regulating mechanism therefor.

The type of oil stove burner known as the wickless burner consists of a bowl having a deep annular channel within which the level of oil is varied to regulate the height of the flame. Usually the oil level is varied by raising or lowering the burner bowl with reference to a constant level source, the source and bowl being suitably connected by a communicating oil supply system. The invention aims to provide an improved regulating mechanism which, in the present instance, is applied to the burner to raise and lower the level of the oil therein.

Ordinarily burners of this type are regulated by means of a lever or the like and frictional engagement between the parts is depended upon to maintain the burner in the desired position of adjustment. This arrangement has proven unsatisfactory for the reason that it frequently happens that the burner is apt to vary its position through failure of the sustaining means to withstand shocks and jars with the result that the height of the burner flame is also varied.

The primary object of this invention is to provide an improved adjusting means which is readily and conveniently operable to adjust an oil receptacle into a desired position and which sustains the receptacle in such position against accidental movement, or until the regulating means is positively operated.

A particular object of the invention is to provide adjusting means including a screw providing a combined operating and sustaining member.

In the accompanying drawings there is illustrated an exemplary embodiment of the invention as applied to the burner showing parts arranged for practical utility and chosen for simplicity of construction.

In the drawings Figure 1 illustrates a view in elevation of a portion of a stove embodying a wickless oil burner.

Fig. 2 is a side elevation partly in section of the stove portion shown in Fig. 1, looking from the right toward Fig. 1.

Fig. 3 is a view similar to Fig. 2 but looking from the left toward Fig. 1.

Fig. 4 is a rear view of the device of Fig. 1.

In the following description of the invention illustrated in the drawings, it will be understood that the arrangement of the parts and the construction herein illustrated and described is in no way a limitation of the invention to the precise disclosure. Those skilled in the art will readily understand that the invention contemplates changes in construction as well as other arrangements of the parts of the device in accordance with the spirit and scope of the invention as expressed in the appended claims.

In the drawings I have shown one of the usual group of burners ordinarily independently mounted for up and down movement relative to a fixed constant level oil supply (not shown). The burner bowl 5 in the present instance constitutes the oil chamber or receptacle which is raised and lowered. This burner bowl has the usual annular channel 6 and is carried by a suitable mounting means such as a bracket 7 vertically adjustable with reference to the stove body, a portion of which is shown at 8 in the form of a front plate. A common fuel supply pipe 9 from the oil source carries for each burner an oil riser 10 which is preferably welded to the main pipe 9, as shown at 11 to form a smooth and tight joint.

The burner bowl 5 carries a fuel pipe 12 which telescopes into the riser 10 through a stuffing box 13. Any other and equivalent connection may be employed but the telescoping connection is preferred since it forms a rigid slidable connection which furnishes a certain degree of lateral support for the burner bowl and constitutes in part the mounting means for the burner.

Extending rearwardly from the front plate 8 is a bracket member 14 secured by right angular ears 15 to the front plate. Top and bottom flanges 16 are provided on the plate member 14 through which the oil riser 10 extends to produce rigidity. The riser 10 is preferably fixed to the topmost of the flanges 16 by nuts 17 engaging threads 18 ahead of the nut of the stuffing box 13.

In addition to the support furnished the burner by the telescoping oil connections, a

guiding means is provided to hold the burner properly positioned. This takes the form of a slot 19 in the bracket plate 14 and a stud on the plate 7 in the form of a nut and bolt structure 20 to ride in the slot, plates 7 and 14 being thus held flat against each other. Vertical motion of the bowl is thus permitted by the structure already described, the bolt and slot serving to limit 10 the range of the vertical motion.

To produce vertical motion and to hold the bowl in any vertical position chosen, I provide means including in the present instance a worm or screw having an operating handle located forwardly of the front plate and operatively associated with the burner so that in the rotation of the screw the burner will be raised or lowered. The threads of the screw in cooperation with a 20 second or thread engaging member serve to lock the parts against displacement except by rotation of the screw.

More specifically, there is provided on the bracket 14 a mounting means for a rotatable screw. The means in the present instance comprises spaced U-shaped lugs 21 having upwardly opening recesses 22 into which a screw shaft 23 is placed, the shaft extending through a hole 24 in the stove 30 body, and being provided with an operating knob 25 at the end. In the present instance the recessed lugs 21 serve as bearings for the screw shaft and also as means to hold the shaft against longitudinal sliding by the 35 provision of a reduced portion 26 at one end of the shaft forming a shoulder 27 which abuts one lug 21, and by the provision of an enlarged threaded portion forming a worm screw 28 which abuts the other lug.

40 Various motion transmitting means may be provided between the rotatable screw and the vertically movable structure. Preferably a swinging member is included in this means to impart vertical motion to the burner. This is accomplished through an arm 29 pivoted at 30 to swing in a vertical plane. The arm 29 preferably engages with the plate 7 carrying the burner by a slot and pin connection. In the present instance a 45 slot 31 is provided in the arm 29 and the pin of this connection is furnished by the head end of the bolt of the aforesaid nut and bolt structure 20, the other end of which bolt rides in the slot 19.

55 In the present instance where the screw threaded member is axially fixed between the lugs 21, a movable thread engaging member is provided to mesh with the screw 28. This takes the form as shown in the drawings of a second swinging member having a projecting portion such as the teeth 32 which mesh with the threads of the screw, the structure constituting a gear segment 33 which is mounted to swing in a vertical 60 plane. To simplify the structure the two

swinging members 29 and 33 are made integral and swing on the common pivot 30. They thus constitute a structure which is in effect a bell crank.

70 For the convenience of the operator in adjusting the position of the burner bowl, an arrow 34 is formed on the frame and an indicator 35 is employed in the form of a plate bearing suitable legends as shown in Fig. 1.

75 The structure hereinabove described permits of a minimum number of parts and of economy in manufacture. The recess-bearings 21 also permit ease in assembly since the shaft 23 is merely dropped in place in 80 the half bearings of recesses 22 and the gear segment 33 positioned over the screw 28 to lock the shaft in its fixed position in the bearings.

85 In operating the burner described, one merely grasps the knob 25 and turns it to the right or left to raise or lower the burner. The worm 28 turns the bell crank comprising gear segment 33 and the arm 29 so that the end of the arm has a substantially vertical motion transmitted through the slot and pin connection to the upright support 7. Thus the upright support 7 and the burner bowl are raised or lowered in a truly vertical plane, being guided in part in the motion by the telescoping oil pipes and the adjacent plates 7 and 14. It is clear that no amount of pressure on the bowl or on the gear segment will cause displacement of the bowl without an accompanying rotation of 95 the screw adjusting shaft 22.

100 This structure is more advantageous than the lever structures ordinarily employed because by the provision of a rotatable adjusting member, the latter is less subject to accidental displacement than such a lever. Furthermore the knob 25 which is grasped by the operator's hand may always be found in the same location irrespective of its degree of angularity, thus enabling the operator to quickly and readily adjust the burner at all times.

105 While the device has been described particularly with reference to burners, it is to be understood that the principles of construction are equally applicable to other oil containers and furthermore that the horizontal and vertical positions and directions herein described are not limited to such except in so far as necessitated by the very nature of the invention.

110 I claim as my invention:

115 1. A wickless oil burner comprising, in combination, a stove body, a burner bowl, a vertical fuel supply pipe, a pipe connected to and carried by the bowl telescoping with the vertical supply pipe, a vertically movable support for the bowl, a pivoted arm having a pin and slot connection with said support, 120 a shaft rotatable in the stove body, a worm 125

on said shaft, and a worm-wheel segment rigid with said pivoted arm, said segment being formed about the pivot center of the arm, and said segment being in mesh with the worm.

2. A wickless oil burner comprising, in combination, a stove body, a burner bowl, means establishing communication between said bowl and an oil supply of substantially constant level, a vertically movable support for said bowl, guiding means for the vertical movement of said support and bowl, a rotatable shaft axially fixed in the stove body, a worm on said shaft, and a bell crank pivoted to the stove body, one arm of the bell crank having teeth forming a gear segment meshing with the worm, and the other arm having a sliding and positive connection with said support whereby swinging of the arm moves the support vertically.

3. In a wickless oil stove, in combination, a frame, an oil container adapted to be positioned to change the level of the oil therein to regulate a flame, a support for said oil container adapted for vertical movement relative to the frame, a communicating oil pipe connected to said container, said pipe being adapted to permit vertical adjustment of the container, a lever pivoted on said frame having a substantially horizontal arm, and a connection between said arm and said support whereby swinging of the lever raises and lowers the support, a rotary shaft axially fixed in said frame, a worm rigid on said shaft, and a gear segment meshing with said screw and arranged to move said lever.

4. A wickless oil burner comprising, in combination, a burner bowl, a vertically movable mounting plate therefor, telescoping oil supply pipes to said bowl, a fixed vertical bracket plate, said two plates being relatively slidable in faced relation to each other, a rotary shaft, bearing members projecting from said bracket plate, a shaft axially fixed

in said bearing members, a screw on said shaft, a gear segment pivoted to said bracket plate to mesh with said screw, an arm rigid with said segment overlying said mounting plate, and a pin passing through said mounting plate, said arm having a radial slot and said bracket plate having a vertical slot therein for said pin.

5. In a burner regulating mechanism, a bracket plate, spaced hooked or half bearings on said plate, a shaft set into said bearings, a screw portion on said shaft between said bearings, and a gear segment meshing with said screw and pivoted to said plate in position to hold said shaft fixed in said bearings.

6. A wickless oil burner comprising, in combination, a burner bowl, means communicating with said bowl for the supply of oil thereto, a support for said bowl, said support being movable vertically for the adjustable positioning of said bowl, a pivoted lever having operative connection with said support, and a rotatable screw member having operative connection with said lever whereby the rotation of said screw member effects the raising and lowering of said support.

7. A level regulating mechanism for fuel oil burners comprising, in combination, an oil receptacle, an adjustable support for said receptacle, means for guiding the adjusting movement of said support in a vertical path, a pivoted lever having operative connection with said support, a rotatable member having a screw threaded portion, and another member in cooperative engagement with said screw threaded portion, one of said members having operative connection with said lever whereby the rotation of said rotatable member effects the raising and lowering of said support.

In testimony whereof, I have hereunto affixed my signature.

CHARLES M. FITCH.
